(57) **CLAIM**

The ornamental design for a skirt, as shown and described.

DESCRIPTION

FIG. 1 is a front perspective view of a skirt showing my new design;

FIG. 2 is a front elevation view thereof showing an outer layer folded upward away from an inner layer;

FIG. 3 is a rear elevation view thereof;

FIG. 4 is a top view thereof;

FIG. 5 is a bottom view thereof showing separation of the outer layer and the inner layer; and,

FIG. 6 is a right side elevation view thereof, the left side elevation view being the same as the right side elevation view.
